UNITED STATES PATENT OFFICE.

SAMUEL M. CURWEN AND JOHN A. BRILL, OF PHILADELPHIA, PENNSYLVANIA; SAID CURWEN ASSIGNOR TO SAID BRILL.

RAILWAY-CAR.

SPECIFICATION forming part of Letters Patent No. 634,396, dated October 3, 1899.

Application filed April 15, 1898. Serial No. 677,644. (No model.)

To all whom it may concern:

Be it known that we, SAMUEL M. CURWEN and JOHN A. BRILL, citizens of the United States, residing at Philadelphia, county of 5 Philadelphia, and State of Pennsylvania, have made certain new and useful Improvements in Railway-Cars, of which the following is a specification.

Our invention relates to improvements in 10 the construction of the class of cars usually employed for electric or cable traction on street-railways, and more particularly to the class of cars having a closed body and platforms that extend therefrom at opposite ends, 15 upon which platforms seats are provided, and which are known as "composite" cars.

One object of our invention relates to a 20 construction whereby the platforms are brought to a level lower than the car-floor, in which construction we utilize, in addition to the usual car-sills, other sills that extend wholly beneath the car-body, which sills are bent downwardly at or about the ends of the 25 closed body and then extend forwardly beyond the ends of the body, upon which sills the platforms are in the main supported. By these means we are enabled to provide a single step for ingress and egress to and from the car.

30 Another portion of the invention relates to an improved construction of the buffers in connection with the sills above mentioned and the connection of the knees of the platform with the car-body and with said buffers.

35 Another portion of our invention relates to the peculiar construction of the parts, wherein we provide sills composed of angle-irons, the dependent parts of which face outwardly and at their outer ends are connected with 40 buffers also formed of angle-irons, having the depending portion extending outwardly, and in other novel details of improvement and combinations of parts that will be more fully hereinafter set forth and then pointed 45 out in the claims.

Reference is to be had to the accompanying drawings, forming part hereof, wherein—

Figure 1 is a side elevation of a railway-car embodying our improvements, the truck 50 for the car not being shown. Fig. 2 is an enlarged detail side elevation of one end of the

car, showing in sectional detail the arrangement of the sills for the platform and their connection with the body of the car and with the truck. Fig. 3 is a vertical cross-section 55 through the platform of the car shown in Fig. 2. Fig. 4 is a detail plan view showing the connection of the buffer with the longitudinal sills of the platform. Fig. 5 is a side elevation thereof. Fig. 6 is a section on the plane 60 of the line *a a* in Fig. 4. Fig. 7 is a detail plan view of the front portion of the platform and buffer. Fig. 7^a is a detail plan view of the front portion of the buffer, showing a modified connection of the side sills and buffer and the platform-knees and the main 65 sills of the platform. Fig. 8 is a side elevation of the same parts. Fig. 8^a is a section on the plane of the line *b b* in Fig. 7, looking in the direction of the arrows; and Fig. 9 is 70 a vertical cross-section through the lower part of the car-body and a truck on the plane of the line *x x* in Fig. 2, showing the connection of the truck with the car-body and the arrangement of the side sills in connection 75 with the truck.

In the accompanying drawings, in which similar numerals and letters of reference indicate corresponding parts in the several views, 1 indicates generally the body of a car, 80 which is of the closed type and may be of any suitable construction.

2 are the side sills of the car-body, and 3 is the floor of the car, connected therewith in any suitable manner, 4 being the skin or 85 outer walls of the car-body, connected with the sills 2.

At 5 are longitudinal sills that are located beneath the sills 2 of the car-body and which form elements of the car construction entirely independent of the car-framing, which 90 may be in the usual manner or as desired and which may be removed without disturbing the integrity of the car-framing proper.

The sills 5 are shown made of angle-irons, 95 having the depending web 5^a located on the outer sides, as shown clearly in Figs. 2, 3, 6, and 9, although as to certain features of our invention their specific form is unimportant. These sills 5 may be secured to the sills 2 by 100 bolts or in any other suitable manner, and at or near the ends of the car-body the sills 5

are bent downwardly at 5^b a suitable distance and thence extend forwardly at 5^c to constitute a part of the support for the platforms, the cross door-sill c and the flooring 6 of which are laid above such sills at the ends, if desired, other means being provided for forming the platforms. For convenience of description we will term the parts 5^c of the sills 5 the "platform-arms." At their outer ends these arms 5^c of the sills 5 are shown beveled upwardly on their undersurfaces at 5^d , and at their outer ends they are connected with buffers 7 . These buffers are shown in the form of angle-irons, having the depending wall 7^a extended outwardly and overlying the wall 5^a of the arms 5^c of sills 5 . The buffers 7 are shown curved where they join the arms 5^c , and these arms at 5^e fit snugly against the buffers. The depending webs 5^e 7^a may be rigidly secured together. The horizontal webs 5^g of the platform-arms 5^c and the horizontal web 7^b of the buffer 7 are secured together by bolts 10 , which also pass through boards 11 , that lie upon the arms 5^c and form part of the flooring or structure of the platform. The crown-piece 12 of the platform is also secured between the webs 5^g and 7^b of the platform-arms 5^c and the buffers 7 , respectively, and we have shown said parts as secured together by stanchions 13 , that assist in supporting the roof or hood 1^a of the platform, for which purpose said stanchions are shown, provided at their lower ends with screw-threads 13^a , that receive nuts 14 , the lower ends of the stanchions 13 being reduced in size and passed through suitable apertures in the webs 5^g 7^b and the crown-pieces 12 . (See Fig. 6.) By preference the stanchions 13 are provided with feet or shoulders 15 , that rest upon the web 7^b . These feet 15 may be integral with the stanchions, or they may be in separate pieces, like a ferrule, the upper edges of which abut against a shoulder 13^b on the stanchion 13 . (See Fig. 6.)

The simplest form of connection between the side sills 5 and the buffers 7 is illustrated in Figs. 7 and 8, as above described. In some cases, however, we find it convenient to connect the outer ends of sills 5 to the buffers 7 through the medium of sockets A , as shown in Figs. 4, 5, 7^a, and 8^a, which consist of angle-pieces having a horizontal web a and a vertical web b . The horizontal web a lies under the horizontal web 7^b of the buffer 7 . The vertical web b lies against the vertical wall 7^a of the buffer, and the outer end of the sill 5 passes into said socket, as clearly shown in Figs. 4 and 7^a. In this connection it will be seen in said figures that the extreme outer end of the sill 5 is curved or cut away at 5^e to correspond to the curve of the buffer. Bolts 8 secure the wall b of socket A to the vertical wall 7^a of buffer 7 , and, as indicated, the extreme outer end a' of socket A extends beyond the horizontal web a thereof and receives the bolt 8 at that point. In addition bolts 9 pass through the vertical web 7^a of the buffer, the vertical web 5^a of sill 5 , and the vertical web b

of socket A . This construction materially strengthens the parts.

From the foregoing it will be seen that the sills 5 extend longitudinally beneath the car-body the entire length of the same and project outwardly therefrom at both ends thereof, being bent down at the ends of the car-body to provide the sill or additional means for supporting a platform that is lower than the floor of the car-body, and that the buffers 7 are secured to the outer ends of these sills, thus forming, together with the arms 5^c of the sills 5 , a skeleton framing for the platforms. The buffers 7 brace the arms 5^c laterally, and the crown-pieces 12 also tie the ends of the arms 5^c together to prevent them from spreading apart. The buffers 7 are further braced in the longitudinal direction of the car, and supports for the flooring of the platforms are provided by means of platform-knees 16 17 . The knees 17 are shown in the form of beams that extend on substantially the same plane as the arms 5^c of the side sills 5 to a point about under the door-sill c , from whence the beams bend upwardly and extend to a cross-beam d , secured to the bottom of the car. The knees 17 also extend forwardly to and abut against the buffers 7 , the horizontal webs 7^b of which overlie the ends of the knees 17 , to which they are secured by bolts 18 . (See Fig. 7^a.) The knees 16 are shown in the form of angle-irons that extend from the buffer 7 on substantially the same plane as the knees 17 to a point beneath the door-sill c , from whence they extend upwardly to and are connected with the beam d . (See Fig. 2.) As shown in Figs. 7^a and 8^a, the buffers 7 are provided with sockets 19 , that are secured by bolts 19^a to the inner faces of the depending webs 7^a of said buffers, to which sockets said knees 16 are secured. (See Fig. 7^a.) The crown-pieces 12 are shown lying upon the knees 16 17 , to which they are bolted or otherwise secured. It will thus be seen that the framing for the platform is composed of the arms 5^c of the sills 5 , the buffers 7 , the knees 16 17 , the crown-pieces 12 , and the boards 11 , upon which the flooring 6 of the platforms is placed and suitably secured. In Fig. 3 the beams 11 are shown as provided on their upper inner edges with recesses 11^a , in which the boards 6 rest, and on their lower edges the boards 11 are shown provided with recesses 11^b , in which the webs 5^g of the arms 5^c rest. By this means the boards 11 are braced laterally in two directions, and the boards 6 of the platform also serve as lateral braces for the arms 5^c .
20 are the steps for the platforms, which are carried by the platform-arms 5^c . For this purpose we have shown hangers 21 , secured to and depending from the arms 5^c of the sills 5 , and at the lower ends of these arms is placed a board 22 , that is turned on edge to receive the thrust of passengers' toes, and the step or tread 23 is pivotally connected with the hangers 21 , so that it may be turned down in position to receive passengers, as shown in

Fig. 3, or turned up parallel with the hang-
ers 21.

The car body and platform constructed as above described may be mounted upon any suitable truck. In the arrangement we have shown the truck-frame 25 is shorter than the car-body 1, so that the car-body projects beyond the ends of the truck. (See Fig. 2.) The top chord 25^a of the truck (or its equivalent) is secured to a subsill 26, and the latter in its turn is secured to the side sills 2, so as to provide means for separably securing the truck and the car. We utilize the angle-iron sill 5 as part of the means for retaining the car body and truck in position laterally relative to each other, and for this purpose we have shown the subsill 26 as provided with a recess 27 on its upper outer surface, which receives the horizontal web 5^a of the sill 5, the subsill 26 at one part thus resting against the sill 2 of the car-body. (See the detail section in Fig. 2.) The subsill 26, top chord 25^a, and the sill 2 may be secured together in any suitable manner, and as the sill 5 is secured to the sill 2 the truck-frame is securely held and prevented from lateral movement under the car-body. By means of the arrangement shown one truck can be readily removed from the car-body and another substituted, and vice versa. The angle-iron sill 5 not only strengthens the car-body both vertically and laterally, but also strengthens the chord 25^a of the truck-frame, and the truck is, furthermore, held in perfect alinement with the car-body, because the depending web 5^a of sill 5 by abutting against the outer face of the subsill 26 prevents said chord from having pivotal movement relatively to the car-body. Thus the car body and truck are firmly united together in every direction.

The form of construction shown and described enables us to make the car-body of ordinary width at the bottom and to put the truck-frame close up against the inner part of the angle-iron sill 5, as shown in Fig. 9, and we are enabled to put the elliptic spring 29 or other form of spring on the extension of the truck-frame under the depressed portion of the platform, carrying the spring well out toward the end of the car-body.

Upon the platform 6 any suitable number of seats 28 may be provided in suitable manner, thus producing a composite type of car having a closed body and external seats at the end or ends thereof.

We do not limit our invention to the precise details of construction and arrangement of parts shown and described, as they may be varied without departing from the spirit thereof.

Having now described our invention, what we claim is—

1. The combination of a car-body having the usual longitudinal side sills, and a truck, the car-body having ends overhanging or projecting beyond the truck, and the latter being separable from or independent of the car-

body, with supplemental sills located below the side sills and which are centrally elevated to receive the truck and which extend longitudinally beneath the car-body and project outwardly from the end thereof to form a depressed support for the car-platform, said sills forming the said ends, substantially as described. 70

2. The combination of a car-body having longitudinal side sills, and a truck, the car-body having one or more end platforms overhanging or projecting beyond the truck, supports for said platform, the truck being separable from and independent of the car-body, the supplemental sills extending longitudinally beneath the side sills, which supplemental sills are bent downwardly at or near the end of the car-body and project outwardly from said bent portions to form additional supports for the car-platform, substantially as described. 80

3. The combination of a car-body having the usual longitudinal side sills, and a truck, the car-body having one or more end platforms overhanging or projecting beyond the truck, supports for said platform, the truck being separable from or independent of the car-body, with supplemental sills extending longitudinally beneath the side sills, which supplemental sills are bent downwardly at or near the end of the car-body and project outwardly from said bent portions to form additional supports for the car-platform, and a buffer secured to the outer ends of said supplemental sills, substantially as described. 90

4. A car-body having a central box portion with longitudinal sills, open sections having a depressed platform extending from the ends 105 of the box portion, and supplemental longitudinal sills extending under both the box and open portions to form an additional support for the same, substantially as described.

5. The combination of a car-body and a truck, the car-body having ends overhanging or projecting beyond the truck, and the latter being independent of the car-body, with sills extending longitudinally beneath the car-body, said sills being composed of angle-iron having the depending web extended outwardly and projecting from the end of the car to provide a support for the car-platform, substantially as described. 110

6. The combination of a car-body having 120 longitudinal sills 2, with sills located beneath the sills 2 and extending throughout the length of the body and projecting therefrom to form a support for the car-platform, substantially as described. 125

7. The combination of a car-body having longitudinal sills 2, with sills composed of angle-iron extending beneath the sills 2 and having the depending webs extended outwardly, said sills projecting from the end of the car-body to form a support for a platform, substantially as described. 130

8. The combination of a car-body having longitudinal sills 2, with sills extending be-

neath the same throughout the length of the car-body and bent downwardly at or near the end thereof, said sills projecting outwardly from the bent portions thereof to form a support for a platform, substantially as described.

9. The combination of a car-body having sills 2, with sills composed of angle-iron located beneath the sills 2 and bent downwardly at or near the end of the car, said sills projecting outwardly from the car-body to form a support for a platform, substantially as described.

10. The combination of a car-body having longitudinal sills 2, with sills located beneath the sills 2 and extending throughout the length of the body and projecting therefrom to form a support for a platform, and a buffer secured to the ends of said sills, substantially as described.

20 11. The combination of a car-body having longitudinal sills 2, sills composed of angle-iron extending beneath the sills 2 and having the depending webs extended outwardly, said sills projecting from the end of the car to form a support for a platform, and a buffer secured to the ends of said sills, substantially as described.

12. The combination of a car-body having longitudinal sills 2, sills extending beneath the same throughout the length of the car-body and bent downwardly at or near the end thereof, said sills projecting outwardly from the bent portions thereof to form a support for a platform, and a buffer secured to the ends of said sills, substantially as described.

30 13. The combination of a car-body having sills 2, with sills composed of angle-iron located beneath the sills 2 and bent downwardly at or near the end of the car, said sills projecting outwardly from the car-body to form a support for a platform, and a buffer secured to the ends of said sills, substantially as described.

40 14. The combination of a car-body, with sills extending longitudinally beneath the same and projecting from the end thereof to provide a support for a platform, with a truck having top chords that are secured to said sills, whereby said chord is braced laterally relatively to the car-body, substantially as described.

50 15. The combination of a car-body having sills composed of angle-iron extending longitudinally of said body beneath the same and projecting from the end thereof, one web of said angle-iron depending from the car-body, with a truck having top chords that are secured within the depending webs of said sills, substantially as described.

60 16. The combination of a car-body, sills extending longitudinally thereof and projecting from the end of the body to form a support for a platform, said sills being composed of angle-iron having the depending webs extended outwardly, with a truck having top chords received within said depending webs, whereby said chords are braced laterally rela-

tively to the car-body, substantially as described.

17. The combination of a car-body having the sills 2, with supplemental side or exterior sills composed of angle-iron extending longitudinally beneath the same and projecting from the end thereof, with a buffer composed of angle-iron secured to the end of said sills, substantially as described.

18. The combination of a car-body having the sills 2, with supplemental side or exterior sills composed of angle-iron extending longitudinally beneath the car-body and projecting from the ends thereof, the depending webs of said sills being extended outwardly, with a buffer composed of angle-iron having the depending web extended outwardly and its top web overlying the ends of said sills and secured to said sills, substantially as described.

19. The combination of a car-body, with sills composed of angle-iron extending longitudinally beneath the same and projecting from the end thereof, the depending webs of said sills being extended outwardly and projecting at the outer ends beyond the horizontal webs of said sills, and with buffers composed of angle-iron secured to said depending webs, the horizontal web of said buffer overlying the ends of the sills, substantially as described.

20. The combination of a car-body, with sills composed of angle-iron extending longitudinally beneath the same and projecting from the end thereof, the outer ends of said sills being curved inwardly, and with a buffer composed of angle-iron having its depending web extended outwardly, the horizontal web of said buffer overlying the ends of the sills, and bolts securing the depending webs of said sills to said buffer, and a platform built upon said sills, substantially as described.

21. The combination of a car-body, with sills composed of angle-iron extending longitudinally beneath the same and projecting from the end thereof, the depending webs of said sills being extended outwardly, a buffer composed of angle-iron having its depending web extended outwardly and in front of the outer ends of said sills, the horizontal web of said buffer overlying said sills, a crown-piece extending between said sills, and means for securing said sills, buffer, and crown-piece together, substantially as described.

22. The combination of a car-body, with sills composed of angle-iron extending longitudinally beneath the same and projecting from the end thereof, the depending webs of said sills being extended outwardly, a buffer composed of angle-iron having its depending web extended outwardly and in front of the outer ends of said sills, the horizontal web of said buffer overlying said sills, a crown-piece located between said sills and the buffer and connecting said sills, and means for securing said sills, crown-piece and buffer together, substantially as described.

23. The combination of a car-body, with

- sills composed of angle-iron extending longitudinally beneath the same and projecting from the end thereof, the depending webs of said sills being extended outwardly, a buffer 5 composed of angle-iron having its depending web extended outwardly and in front of the outer ends of said sills, the horizontal web of said buffer overlying said sills, a crown-piece connecting the ends of said sills, and stanchions extending from said sills to the roof or hood of the platform, substantially as described.
24. The combination of a car-body, with sills composed of angle-iron extending longitudinally beneath the same and projecting from the end thereof, the depending webs of said sills being extended outwardly, a buffer composed of angle-iron having its depending web extended outwardly and in front of the outer ends of said sills, the horizontal web of said buffer overlying said sills, and stanchions passing through apertures in said sills, buffer, and crown-piece and connected with the roof or hood of the platform, said stanchions having nuts to secure the parts together, substantially as described.
25. The combination of a car-body, with sills composed of angle-iron extending longitudinally beneath the same and projecting from the end thereof, the depending webs of said sills being extended outwardly, a buffer composed of angle-iron having its depending web extended outwardly and in front of the outer ends of said sills, the horizontal web of said buffer overlying said sills, stanchions having reduced ends passing through apertures in said sills, buffer, and crown-piece, shoulders on said stanchions, foot-pieces abutting against said shoulders and against the buffer, and nuts on said stanchions for holding said parts together, substantially as described.
26. The combination of a car-body, with sills extending longitudinally beneath the same and projecting from the ends thereof, a buffer composed of angle-iron having the depending web extended outwardly and the horizontal web overlying the ends of said sills, said sills and buffer being secured together, and with knees extending from the body and secured to said buffer, the horizontal web of said buffer overlying said knees, substantially as described.
27. The combination of a car-body, with sills extending longitudinally beneath the same and projecting from the end thereof, a buffer composed of angle-iron having the depending web extended outwardly and the horizontal web overlying the ends of said sills, 55 sockets carried by the depending web of said buffer, and knee-pieces composed of angle-iron extending from the car-sill and secured to said sockets, substantially as described.
28. The combination of a car, with sills extending longitudinally beneath the same and projecting from the end thereof, a buffer se- 60 cured to the ends of said sills, and a platform-knee secured to said buffer and extending beneath the door-sill and there bent upwardly and extended to the bottom of the car to which it is secured, substantially as described.
29. The combination of a car-body, with sills extending longitudinally beneath the same and projecting from the end thereof, a buffer secured to the ends of said sills, a platform-knee secured to said buffer and composed of angle-iron extending from said buffer rearwardly beneath the door-sill, and there bent upwardly and extended to the bottom of the car to which it is secured, substantially as described.
30. The combination of a car-body, with sills extending longitudinally beneath the same and projecting from the end thereof, a buffer secured to the ends of said sills, a platform knee-piece extending from said buffer to a point beneath the door-sill and there bent upwardly and extended rearwardly, and a beam secured to the bottom of the car-body, said knee being secured to said beam, substantially as described.
31. The combination of a car-body, with sills extending longitudinally beneath the same and bent downwardly at or near the end of the car-body, said sills projecting outwardly from the car-body, a knee-piece extending from the buffer on substantially the same plane as the projecting ends of the sills and to a point beneath the door-sill, said knee-piece being there bent upwardly and extended rearwardly and connected with the car-body, substantially as described.
32. The combination of a car-body, with sills extending longitudinally beneath the same and bent downwardly at or near the end of the car-body, said sills projecting outwardly from the car-body, a knee-piece extending from the buffer on substantially the same plane as the projecting ends of the sills and to a point beneath the door-sill, said knee-piece being there bent upwardly and extended rearwardly, and a beam connected with the bottom of the car, said knee-piece being secured to said beam, substantially as described.
33. The combination of a car-body, with sills extending longitudinally beneath the same and projecting from the end thereof, boards secured upon said sills, a crown-piece connecting said sills, a buffer composed of angle-iron secured to said sills and to said crown-piece, and platform-knees extending from the body of the car to said buffer, the crown-piece being secured to the knees, substantially as described.
34. The combination of a car-body having usual longitudinal sills, with supplemental sills extending longitudinally beneath the same and projecting from the end thereof to form a support for a platform, and hangers secured to the downwardly-projecting portions of said sills, and a step connected with said hangers, substantially as described.

35. The combination with a sill 2, of the supplemental sill 5 having a depending flange 5^a, hangers 21 fixed to said flange, and a step secured to said hangers, substantially as described.

36. A car comprising a box portion 1 having sills 2 and depressed and open end sections 6, the supplemental sills 5 under the sills 2 and depressed to support the sections 6, a truck under the sills 5 at the box portion and steps secured to the sills 5 at the sections 6, substantially as described.

37. A car having supplemental sills 5 with downwardly-deflected portions 5^b, the horizontal extensions 5^c, both portions 5^b, 5^c, having a lateral flange 5^e and pendent web 5^a, combined with a truck having a top chord 25^a exterior to the wheels on which the sills 5 are supported, the chord being below the flange 5^e, the web 5^a being outside of said chord, said truck having a spring-base extending into the portion 5^b under the flange 5^e and within the web 5^a, substantially as described.

38. A car having the supplemental sills 5 provided with the lateral flanges 5^e with downwardly-deflected portions 5^b and horizontal extensions 5^c combined with a truck on which the sills 5 are supported, said truck having a frame 25 and a top chord 25^a, the plane of the flange 5^e at the extensions 5^c being interme-

diate of the top chord and truck-frame, substantially as described.

39. The buffer 7 having the lateral flange 7^b and pendent web 7^a, the sill 5 having a lateral flange 5^e and the pendent web 5^a, the buffer and sill being secured together, the crown-piece 12 the end of which is interposed between the said flanges, and a bolt tying the flanges and crown-piece together, substantially as described. 35 40

40. The combination of a car-body having longitudinal sills 2; with sills located beneath the sills 2 and extending throughout the length of the body and projecting therefrom 45 to form a support for a platform, a buffer connecting the ends of said latter sills; and sockets secured to said buffer, into which said sills project, substantially as described.
